(57) **CLAIM**

The ornamental design for a sinker for a knitting machine as shown and described.

DESCRIPTION

FIG. 1 is a perspective view of a first embodiment of a sinker for a knitting machine;

FIG. 2 is a top plan view thereof;

FIG. 3 is a bottom plan view thereof;

FIG. 4 is a left-side elevational view thereof;

FIG. 5 is a right-side elevational view thereof;

FIG. 6 is a front elevational view thereof;

FIG. 7 is a rear elevational view thereof;

FIG. 8 is a perspective view of a second embodiment of a sinker for a knitting machine;

FIG. 9 is a top plan view of the sinker of FIG. 8;

FIG. 10 is a bottom plan view of the sinker of FIG. 8;

FIG. 11 is a left-side elevational view of the sinker of FIG. 8;

FIG. 12 is a right-side elevational view of the sinker of FIG. 8;

FIG. 13 is a front elevational view of the sinker of FIG. 8; and,

FIG. 14 is a rear elevational view of the sinker of FIG. 8.
